COLLAPSIBLE BABY BED

Theodore W. Schettler, Jr., Roswell, N. Mex.

Application July 21, 1948, Serial No. 39,883

1 Claim. (Cl. 5—98)

1

This invention relates to a collapsible baby bed wherein the bed may be erected in a relatively short period of time ready for use, and then be collapsed and rolled up into a small package for portability.

The invention involves a large number of advantages including the structure permitting light weight and strength in actual usage. It is quite rigid when set up, and is made to be durable over a long period of time. The construction lends itself to easy washing in order to permit the entire structure to be maintained in a sanitary condition. There are no slots nor openings in the structure through which the baby might extend its head and get into difficulty as is often the case in the slatted construction. Moreover there are no hinges nor catches which have to be operated intermediate corner posts and the like. The side and end walls are made out of a flexible material that has a delayed elastic quality, while the floor itself being flexible is non-stretchable.

Furthermore the operation of setting up the bed and in collapsing it and reducing it to a small package involves no skill, and may be accomplished in a very short period of time all without the use of any kind of tools whatsoever.

These and many other objects and advantages of the invention will become apparent to those skilled in the art in the following description of one particular form of the invention as illustrated in the accompanying drawings, in which

Fig. 1, is a view in side elevation;

Fig. 2 is a view in top plan;

Fig. 3, a detail in vertical section on the line 3—3 in Fig. 2;

Fig. 4, a view in bottom plan;

Fig. 5, a detail on an enlarged scale in vertical section on the line 5—5 in Fig. 2;

Fig. 6, a detail in vertical section on the line 6—6 in Fig. 5;

Fig. 7, a detail in vertical section on the line 7—7 in Fig. 5;

Fig. 8, a detail in transverse section on the line 8—8 in Fig. 5;

Fig. 9, a vertical transverse section on an enlarged scale on the line 9—9 in Fig. 1;

Fig. 10, a detail in bottom plan view of a corner construction; and

Fig. 11, a detail in vertical section illustrating the attachment of the wall material to the floor material.

Referring to the drawings, in which like characters of reference indicate like parts, I employ four corner posts 15, 16, 17, and 18 respectively,

2

each of these posts in the present showing being made out of square tubing. Top, round rails 19 and 20 interconnect respectively the upper end portions of the posts 15, 16, and 17, 18. Likewise lower rails constituting round tubing and designated by the numerals 21 and 22 interconnect respectively these posts 15 and 16 on the one side and 17, 18 on the other side.

Then interconnecting the upper end portions 10 of the posts 15 and 18, and the posts 16, 17, are the upper end rails 23 and 24 respectively. In like manner lower end rails 25 and 26 interconnect respectively the posts 15, 18 and 16, 17, Fig. 3.

15 The axes of the top side rails 19 and 20, and the end rails 23, 24 lie in the same plane. Also the axes of the lower side rails 21 and 22, and the lower end rails 25 and 26 lie in the same plane. This plane of the lower end and side rails is spaced upwardly a distance from the lower ends of the respective posts as indicated in Fig. 1.

20 The ends of all of these top and bottom side and end rails are detachably interconnected with their respective posts. Reference is made now particularly to Figs. 5—8 wherein the manner of the interconnection of these rails with the posts is illustrated. Since all of the connections are identical, the description of one particular rail connection is sufficient to describe all of the other rail connections.

25 Referring specifically to the top side rail 19 and its connection with the post 15, there is placed inside of the post 15 a plate 27 which has inwardly extending tongues 28 and 29. A cap screw 30 is provided with a special head constituting a washer 31 and a head portion 32 over which a wrench may be engaged. The bolt 30 is inserted through a thimble 33, through the side wall of the post 15 and rotated to screw-threadedly engage between the ends of the opposing tongues 28 and 29 so that the thimble 33 is firmly brought up against the side face of the post 15 to secure that thimble in fixed position.

30 45 The diameter of the washer 31 is made to be less than the internal diameter of the thimble 33 so that the end of the tube 19 may frictionally engage over the periphery of the washer 31 and against the internal wall of the thimble 33. The end of the rail 19 is preferably brought into abutment with the internal end of the thimble 33.

40 A post 34 is provided to slide freely through an opening in the rail 19 so as to extend normally radially outwardly therefrom. The degree of ex-

tension of the post 34 beyond the wall of the tube 19 is determined by the internal head 35 of the post 34, Fig. 6. Then in order to maintain the post 34 in this normal, extended position, there is an elastic medium provided inside of the tube 19, herein shown as a block of sponge rubber 36 which is urged compressively into the end of the tube 19 to bear against the head 35 tending to seat the head against the internal face of the wall of the tube 19. The post 34 may be retracted by pushing its outer end inwardly against the rubber 36. Each of the thimbles 33 is provided with an opening through which the post 34 may extend when the respective rails are brought into the positions as just described in reference to the rail 19 so that the post 34 serves as an interlocking means to prevent withdrawal or displacement of those rails. The post 34 in each instance may be sufficiently retracted to permit the insertion of the rail, rail 19 for example, into the thimble 33 and then allow the post 34 to spring back out through the opening 86 provided in the thimble in matched position for that travel. There is one distinction however to be pointed out between the upper and lower thimbles 33 in respect to those thimbles spaced along any one of the posts. This distinction is that all of the thimbles 33 which are at the upper end portions of the respective posts 15, 16, 17, and 18, have their upper portions cut away to leave simply a short upper collar 37, Fig. 6, which engages only the extreme outer ends respectively of the top side and end rails. The lower thimbles, Fig. 7, are left to have their full circumferential wall throughout the longitudinal length of the thimble. The side and end walls are made out of a synthetic resin or plastic material which has a peculiar property of being elastic, although the elasticity is of a slowly delayed nature. This material is now commercially obtainable.

The side and end walls are made in a continuous length of material including the side panel 40, the end panel 41, the other side panel 42, the other end panel 43, all of these panels being in one continuous strip of material and having the ends of that strip joined one to the other preferably at a corner post, Fig. 1, by vertical stitching 44. The total length of the materials so stitched together forming the rectangular shape is made to be such that the material will require a slight stretching to be taut around the four corner posts. A floor 45 is made out of any suitable material preferably of a non-stretching nature and also water proof besides. One particular material suitable for this purpose is one that is now commonly being made to embody fibers of finely spun glass together with a plastic intermediate bonding material. This floor material 45 is cut to have a total area such that it will exceed the area defined by the side panels 40, 41, 42, and 43 as above indicated. This means that the side and end portions of the floor 45 must be turned to extend along the inner faces of those panels respectively.

For example, an end portion 46 of the floor 45 is turned downwardly along the inner face of the panel 41 and is stitched thereto along the lower common edges by rows of stitching 47. In other words the down turned portion 46 is fixed only to the panel 41 at its lower edge, a distance removed below the normal position of the floor 45. In the same manner, a side portion 48 of the floor 45 is turned downwardly along the inside of the panel 42 and is there stitched along the common lower ends. For increased strength,

the down turned ends of the floor 45, such as the downturned end 46, Fig. 11, is turned upwardly by a short length 49 and ends of tensioning straps 53 and 54 are intersewed between the portion 49 and the lower end of the panel 41 along the end panel 41, and ends of straps 50, 51, 52, along the lower end of the panel 42, between it and the down turned portion 48 of the floor.

The vertical height of the respective panels 40, 41, 42, and 43 is made to be such from the top to the lower edge respectively that the lower ends of those panels will be normally spaced a distance of some 4 to 6 inches below the undersides of the lower side rails 21 and 22, and the end rails 25 and 26. Therefore the floor 45 will have to be spaced upwardly within those panels in order to assume a horizontal, planar condition.

Each of the top end portions of the respective panels 40, 41, 42, and 43 is provided with a hem 55, 56, 57 and 58 respectively.

Now assuming that all of the various parts are in a disassembled condition, the top side rail 19 is inserted through the hem 51 to extend by its ends from each end portion of that hem. It is to be noted that in each instance, the material forming the various panels 40-43 inclusive is cut away by the portions 60 to clear the corner posts when the panels are in their erected positions. The other side rail 20 is inserted through the hem 55; the end rail 23 is inserted through the hem 58; and the end rail 24 is inserted through the hem 56. Then the ends of those rails 19, 20, and 23, 24 are pushed into the respective thimbles 33 of the posts 15, 16, and 17, 18 to have the interlocking post 34 snap into the openings 86 to retain the rails in their positions which will align the posts 15-18 in the rectangular shape as viewed from the top side, Fig. 2. Following that operation, the lower side rails 21, 22, and the lower end rails 25, 26 are fixed in position by having their ends engaged in their respective thimbles 33 with those posts 15-18 inclusive, all as above indicated. Of course these lower rails may be inserted first to support the posts if desired before the upper set of rails are engaged with the posts.

In any event, the side panels 40-43 then can hang from the top set of rails to form a rectilinear box-like container. The panels 40-43, being in one continuous strip as above indicated, extend around the outsides of the posts 15-18 inclusive. Since these panels have a vertical height greater than the distance between the top and bottom sets of rails interconnecting the posts, there are end portions 62, 63, 64, and 65, of the respective panels 40-43 which will hang below the level of the plane of the lower rails 21, 22, and 25, 26. On the insides of these lower panel portions 62-65 are the marginal edge portions of the floor 45 as above described. The floor 45 will be in contact with the top sides of those lower rails 21, 22, and 25, 26.

Now at spaced intervals along the edge of the panel marginal portion 63 there are stitched, as above indicated the straps 53 and 54. In the same manner, along the edge portion 64 of the panel 42 there are stitched in spaced apart relation the straps 50, 51, 52, Fig. 4.

Along the edge of the edge portion 62 of the panel 40 there are stitched in spaced apart relation, the spacing matching that of the straps 50-52 inclusive, straps 66, 67, and 68. These straps have means for permitting extension or retraction of the length of the straps, that is the straps 53, 54, and 66, 67, and 68, have such means

5

consisting of the buckles 69. In the end of each one of these straps there is a hook 70 which may be engaged in a loop 71. Referring specifically to the straps 66, 67, 68, these hooks 70 engage in the loops 71, which loops are secured to the straps 50, 51, and 52. Then the hooks 70 on the ends of the straps 53 and 54 engage in the loops 71 which are secured to the ends of the short straps 72 and 73 which are in turn secured to the edge portions of the lower end portion 65 of the panel 43, Fig. 4.

Thus by means of providing the proper length of the straps 53, 54, and 66-68 inclusive, the hooks 70 thereof may be engaged in the loop 71 to apply considerable tension to those straps, and in turn pull the portion 63 of the panel 41, around under the rail 26 and at the same time pull the edge portion 65 of the panel 43 around under the rail 25 on the other side in order to pull those panels 41 and 43 into a very taut condition. Then the other straps 66, 67, and 68 are pulled up tightly by engaging their respective hook 70 in the respective loop 71 of the straps 50-52 inclusive to pull the edge portions 62 and 64 one toward the other under the bottom rails 22 and 21 respectively.

Now in applying tension to these respective straps, the floor 45 is pulled up tautly and the edge portions secured over the marginal portions of the floor 45 are allowed to stretch along with that pull so that the tension is substantially applied to floor 45 and the edge portions of the panels 40-43 follow along therewith. This is possible by reason of the fact as above indicated, that the floor 45 is made out of substantially non-yielding material whereas the panels of the side and end walls are not only flexible but elastic in the delayed manner indicated.

Referring to Fig. 10, it is to be seen how the various parts are engaged around under the lower rails wherein a corner is shown in detail to indicate the opposite end floor portions 46 and 88 as being pulled around the under sides of the rails 22 and 26 and the panel end portions 62 and 63 overlapping those floor portions 46 and 88. Then in order to secure the corners of the panel portions 62 and 63 for example, Fig. 10, the extreme ends 75 and 76 are provided with component parts 77 and 78 of fasteners such as the usual and well known glove fastener so that one may be compressed over the other as indicated in Fig. 4. The lower corners of the panels 40-43 are cut away as indicated by the numeral 80 in each instance so that the corners will clear the posts and permit the edge portions of the panels to come together at the corners as just indicated.

Referring to Figs. 6 and 7, it was above noted that the upper thimble 33 was cut away from the upper side to leave the short cylindrical portion 37 whereas the lower thimble 33 was left to have the full longitudinal length as indicated in Fig. 7. The reason for this difference is that the lower rails may be inserted into their respective thimbles 33, and then the upper rails 19, 20, and 23 and 24, may be pushed into their thimbles 33 without having to spread apart the posts one from the other too great a distance in opposition to the pull of the surrounding material forming the panels 40-43 inclusive.

Each of the panels 40-43 inclusive is preferably provided with a series of perforations 81 in order to provide ventilation within the space defined by the panels.

6

To disassemble the construction, the various straps are disengaged between their hook 70 and loop 71 to release the tension not only on the floor 45 but also on the side panels 40-43 whereupon the posts 34 at the ends of the top rails may be pushed upwardly to permit disengagement of those top side and end rails from their respective posts, and then the lower set of rails may likewise be disengaged so that the posts and rails may be laid side by side and the panel and floor material wrap therearound if so desired or wrapped separately for convenience and carried in some suitable holder. As soon as the straps are released between their hooks and loops, and the corners are disengaged at the members 77, 78, the entire fabric material may be lifted from the structure as soon as the top set of rails are released from their posts.

While I have herein shown and described my invention in the one particular form, it is obvious that structural changes may be employed without departing from the spirit of the invention, and I therefore do not desire to be limited to that precise form beyond the limitations which may be imposed by the following claim.

I claim:

In a collapsible baby bed, the combination with a framework of corner posts spaced by interconnecting top and bottom side and end rails, of an endless belt of elastic, plastic material to extend in a stretched condition around the outer surfaces of and between said posts to define side and end panels as a complete end closing side wall without gaps at the corners; a flexible, substantially non-stretching floor piece of a greater area than that defined by said lower side and end rails; said belt of elastic material having a height exceeding the vertical distance between said top and bottom side and end rails; the edge portions of said floor piece being secured therewith to said belt of material along a line spaced below the top edges of the material a distance exceeding the distance between the top and bottom rails; means supporting said material by its top edge portion from said top side and end rails; and tensioning means interengaging the opposed, floor piece edge portions across and under said bottom side and end rails to pull the side and end edge portions of the floor piece toward each other respectively to hold said floor piece taut over said bottom and end rails; and simultaneously stretch said material downwardly and around and under those rails all in the absence of pockets receiving the bottom rails.

THEODORE W. SCHETTLER, JR.
